UNITED STATES PATENT OFFICE.

WALTER F. SMITH, JR., OF NEW YORK, N. Y., ASSIGNOR TO WESTERN ELECTRIC COMPANY, INCORPORATED, OF NEW YORK, N. Y., A CORPORATION OF NEW YORK.

TELEPHONE MUFFLER.

Application filed November 21, 1925. Serial No. 70,461.

This invention relates to telephone transmitters and more particularly to voice mufflers which enable one to speak into the transmitter without being overheard by bystanders. These mufflers necessarily entirely enclose the mouth.

An object of the invention is to increase the degree of secrecy obtainable by the use of voice mufflers without sacrificing the efficiency or the clearness of the telephone conversation. Another object is to improve the quality of the speech transmitted to a telephone line through a voice muffler.

As is well known, the human voice contains sound vibrations or frequencies ranging from about 50 cycles per second to frequencies as high as 15,000 cycles per second. Most of the energy is contained in sounds below 300 cycles per second. Intelligibility depends on the sounds of the higher frequencies, and therefore sounds of low frequencies, even though radiated to the atmosphere, are unintelligible, but those of higher frequencies must be suppressed.

In carrying out this invention, a system of filter devices is provided whereby the transmission to the atmosphere of sound waves of high frequencies which would be intelligible is suppressed, and whereby sound waves of low or unintelligible frequencies, including the hollow sounds caused by the natural frequency of the mouthpiece, are prevented from exerting their full force upon the diaphragm of the transmitter. In this acoustic filter system no "back pressure" is generated by the speaker's breath in the muffler mouthpiece, as it is thoroughly exhausted in the atmosphere through the low-pass filters.

Inasmuch as the chamber of the mouthpiece which encloses the mouth is resonant at low frequencies, determined by the design of the mouthpiece chamber, thus making the transmitted speech unnaturally hollow, a high-pass acoustic filter is preferably introduced between the mouthpiece chamber and the transmitter. This filter effectively attenuates all frequencies below a predetermined value.

This invention will be better understood by reference to the accompanying drawings in which Fig. 1 is a front assembly view of a muffler embodying certain features of this invention partially shown in section; Fig. 2 is a top view thereof also partially shown

in section; Fig. 3 is a top assembly view of a modified form of the acoustic filter system shown in Fig. 1 mounted on an ordinary telephone desk set; Fig. 4 is a sectional view taken approximately on line 4-4 of Fig. 3 and looking in the direction indicated by the arrows.

Similar reference characters refer to similar parts throughout the description.

The telephone muffler of this invention preferably consists of an oval shaped mouthpiece 10, on the peripheral edge of which is mounted a band 11 which may be made of any suitable material, preferably felt or rubber, so shaped that it will snugly fit the mouth contour of the operator. The mouthpiece 10 is provided with a wall 12 having a centrally disposed opening 13, in which a bushing 14 provided with a screw threaded nut 15 and collar 15' is adapted to hold the mouthpiece 10 in adjusted position with respect to the particular type of telephone set to which it may be attached.

The opposite portion of bushing 14 is screw threaded and is adapted to fit the threaded portion of the telephone transmitter face plate in replacement of the ordinary telephone transmitter mouthpiece. Preferably tangentially disposed on the mouthpiece 10 and in coaxial alignment are mounted two pairs of identical acoustic filters 16, 17 and 18, 19 shown in Fig. 1. These filters are constructed according to the theory and formulæ given in a paper by G. W. Steward, Vol. XX, No. 6, of the Physical Review of 1922. Each filter consists of an open tube 20 in which a number of radially disposed apertures such as 21 connect with an associated closed drum 22. In such acoustic filters, the dimensions of the tube 20 and the chamber 22 are made such that sound waves contained in the low ranges of frequencies approximately of the order of up to 300 cycles per second are exhausted through to the atmosphere and sound waves contained in the higher ranges of frequencies, that is above approximately 300 cycles per second which may be intelligible to persons in the vicinity of the user if permitted to escape, are strongly attenuated in their passage to the air.

It is obvious that a single filter unit of the type described may be made of such dimensions that it will equal the exhausting capacity of the filters 16, 17, 18 and 19. However, best results

have been obtained by using a combination or a system of filters as shown in Fig. 1. By means of this arrangement the unnaturalness of the sound present in mufflers of 5 the type heretofore used due to the "back pressure" exerted on the transmitter diaphragm is largely eliminated.

Fig. 3 shows a system of filters similar to that shown in Fig. 1 with the addition of a 10 conduit 23 which represents a high-pass filter and which passes sound waves having frequencies above approximately 300 cycles. This tube is coiled and encased in a drum 26 and serves to connect the mouthpiece 10 to 15 the face plate of the telephone transmitter 24. Conduit 23 is provided with a plurality of equally spaced openings 25 shown in Fig. 4 which exhaust into the drum 26. The size of these openings and their spacing 20 with respect to the tube diameter may be proportioned, in accordance with the principles set forth by Stewart in the aforementioned paper, to impart to the filter the ability to transmit sound waves of frequencies greater than about 300 C. P. S. and to 25 attenuate to a certain extent sound waves of lower frequencies. Connection to the free air from the interior of drum 26 is made by filter device 27, which is similar to filters 30 16 and 17. This prevents the escape of such higher frequency sound waves as may be radiated from the holes in filter 23.

What is claimed is:

1. A voice muffler for a telephone transmitter comprising a chamber adapted to form a mouthpiece and a breath exhaust passage leading from said chamber to the open air, said passage comprising a tubular element having an expansion chamber coupled 35 thereto, and being proportioned to substantially suppress the transmission therethrough of sound waves corresponding to the higher frequencies of speech.

2. A voice muffler in accordance with 40 claim 1 in which the breath exhaust passage is proportioned to suppress all sound waves above a frequency at least as low as 300 cycles per second.

3. A voice muffler in accordance with claim 45 1 in which the expansion chamber is con-

nected to the breath exhaust tube at a point intermediate its ends.

4. A voice muffler for a telephone transmitter comprising a chamber adapted to form a mouthpiece and a breath exhaust 55 passage, said passage comprising a tubular element having a side branch passage connected thereto at a point intermediate its ends, the component parts of said exhaust passage being proportioned to substantially 60 suppress the transmission therethrough of sound waves corresponding to the higher frequencies of speech, and to relieve the pressure in the mouthpiece chamber due to waves of very low speech frequencies. 65

5. In combination with a telephone transmitter, a chamber adapted to form a mouthpiece, a breath exhaust passage from said chamber including means adapted to attenuate sound waves corresponding to the higher 70 frequencies of speech, and additional means for relieving excess pressure on the transmitter diaphragm due to the speech waves of low frequencies. 75

6. In combination with a telephone transmitter, a chamber adapted to form a mouthpiece, a breath exhaust passage from said chamber including means for attenuating speech waves of the higher frequencies, and means for compensating the effects of low 80 frequency resonance in said chamber upon the diaphragm of the transmitter. 85

7. A voice muffler for a telephone transmitter comprising a chamber adapted to form a mouthpiece, a sound wave passage 90 adapted to connect said chamber with a telephone transmitter, and a breath exhaust passage leading from said chamber to the open air, said exhaust passage including an acoustic wave filter adapted to attenuate sound waves above a frequency at least as low as 300 cycles per second, and said first mentioned passage including an acoustic wave filter adapted to attenuate speech waves of low frequencies. 95

In witness whereof, I hereunto subscribe my name this 18th day of November, A. D. 1925.

WALTER F. SMITH, JR.
